UNITED STATES PATENT OFFICE.

NATHAN C. SHIVERICK, OF OMAHA, NEBRASKA.

RIDING BOOT AND LEGGING.

1,076,845.

Specification of Letters Patent.

Patented Oct. 28, 1913.

Application filed December 12, 1912. Serial No. 736,407.

To all whom it may concern:

Be it known that I, NATHAN C. SHIVERICK, a citizen of the United States, and a resident of Omaha, in the county of Douglas and State of Nebraska, have invented certain new and useful Improvements in Riding Boots and Leggings, of which the following is a specification.

My invention relates to leg-coverings such as are provided by boots and leggings, and especially to articles of this class designed for use in horseback riding.

It is the object of my invention to provide in an article of this kind a comparatively stiff and smooth-surfaced covering for that portion of the leg between the knee and ankle, the same having a soft and pliable portion adjoining the inner side of the calf of the leg, or the part of the leg which is held against the side of a horse in riding.

Structures embodying my invention are illustrated in the accompanying drawings, in which—

Figure 1 is a view of the right or inner side of a boot for the left foot and leg, Fig. 2 is a transverse horizontal section on the plane of the line $x-x$ of Fig. 1, and Fig. 3 is a similar view showing a modified construction of the article.

Among those engaged in sports or occupations that require horseback riding, leg-coverings, such as boots and leggings, are usually considered as of two general classes, each of which has certain advantages for the rider. In the one class the leg-covering is of comparatively stiff material and this has the advantage of preserving its form and appearance, not wrinkling down around the ankle so as to cause discomfort to the wearer and present an unsightly appearance. In the other class the leg-covering is of soft or pliable material and has the advantage of enabling the rider to feel the side of the horse, and to get a better and more natural "cling" or grip upon the sides of the animal, thus giving the rider a feeling of security and freedom which greatly increases the ease of riding. By my invention the advantages of both the above classes of leg-coverings are combined in a single article.

In the boot illustrated in the drawings the foot-portion 1 is of ordinary construction and materials, and the main part of the leg-portion thereof may be of the same con-

struction as is ordinarily used for stiff-topped riding-boots. The outer part 2 of said leg-portion of the boot is usually and preferably made of a continuous piece of pliable finished leather of which the edges are joined at the back, an external stay 3 being sewed over the joined edges. In the structure shown in Fig. 2 there is a lining-piece 4 of relatively stiff leather which is cemented to the external layer 2, and of which the edges are joined at a position coincident with the juncture of the edges of the outer portion. This stiff lining-piece is cut away throughout an area substantially as shown by the shaded part A of which the front and lower margins are indicated by a dotted line in Fig. 1. Where the stiff lining-piece is cut away a piece 5 of soft leather is substituted therefor, so that said portion of the boot-top is soft and pliable, as distinguished from the remaining relatively stiff portion.

In the modified structure shown in Fig. 3, a stiffening-piece 14 is provided of the same extent as the lining-piece 4 in the first structure, and a soft and pliable lining 15 is employed which extends coincidently with the outer piece 2. Thus the stiffening-piece 14 forms an interlining for the boot-top except at the described portion A.

The extent of the pliable portion of the boot-top is such that when the boot is worn said portion lies over the inner and rearward part of the fleshy portion of the calf of the wearer's leg, extending down toward the ankle to a point at which the muscles begin noticeably to merge or be inserted into the tendons of the ankle. The leg-portion of the boot is thus made soft and pliable throughout the part thereof covering that portion of the leg of the rider adjoining the side of the horse, and the pliable portion is extended far enough around the rearward side of the leg to accommodate a rider who keeps his toes turned far out. The boot-top is thus kept in its proper shape and presents the smooth-surfaced and slight appearance characteristic of a stiff-topped boot, while at the same time it gives to a rider all the advantages of a soft-topped boot.

The boot is especially desirable for military use, and for sports, such as polo, which necessitate a rider being securely seated upon his horse.

While I have shown and described my in-

vention as embodied in a riding-boot, it will be obvious that it is equally applicable to a legging, puttee or other article for covering the leg from knee to ankle.

5 Now, having described my invention, what I claim and desire to secure by Letters Patent is:

1. A leg-covering comprising a body portion of relatively stiff material, and a pliable portion for covering the inner posterior side 10 of the calf of the leg.

2. A leg-covering for riding, comprising a pliable body portion, and means for stiffening the same throughout except in that 15 portion which covers the inner and rearward fleshy portion of the leg below the knee.

3. A leg-covering comprising a body portion of pliable leather, and a lining-piece of stiff leather, the lining-piece extending so as 20 to cover the leg of the wearer except that portion of the leg which is held against the side of a horse in riding.

4. A stiff-topped riding-boot having a

25 pliable portion at the inner and rearward side of the calf of the leg.

5. A riding-boot having a relatively stiff and smooth-surfaced main leg-portion, and a relatively soft and pliable portion extending from the top toward the ankle on the inner and rearward side of the leg.

30 6. A riding-boot having a top-portion with an external layer of relatively soft and pliable leather, and a lining-piece of relatively stiff leather, the lining-piece being substantially coextensive with the boot-top but not extending inside that part of the boot-top covering the inner and rearward side of the fleshy part of the leg below the knee.

35 40 In testimony whereof I have hereunto subscribed my name in the presence of two witnesses.

NATHAN C. SHIVERICK.
